UNITED STATES PATENT OFFICE.

FRANK SMITH, OF ROCKFORD, ILLINOIS, ASSIGNOR OF ONE-TENTH TO MRS. A. G. KERRISON, OF ROCKFORD, ILLINOIS.

FOLDABLE BEDSPRING.

Application filed November 22, 1926. Serial No. 149,807.

This invention relates to a foldable bed spring.

The principal object of the invention is to provide a simple and inexpensive detachable connection for foldable sections of a bed spring frame permitting of the quick and easy attachment and detachment of the frame sections when the bed spring is being set up for use or knocked down for folding the same, as for example when the same is to be moved. By virtue of my improved connection the matter of carrying the bed spring around corners in hallways and up and down stairs is relieved of all of its annoyances as the bed spring when folded up is of sufficiently small and practicable size. Furthermore, the connection is such as to be unnoticeable when the bed spring is set up and mounted in the bedstead, and is also of sufficient sturdiness to give positive assurance against breakage.

The invention is illustrated in the accompanying drawings wherein—

Figure 1 is a perspective view of a bed spring of any standard or preferred type having the end frame sections provided with my improved detachable connection; and

Fig. 2 is a view looking at the inner side of one of the end frame spans showing the angle iron frame sections joined in accordance with my invention, the parts of the connection being shown partly in elevation and partly in section for purposes of better illustration.

The frame of the bed spring 5 comprises the usual side members 6 and end members 7. I prefer to have the end members 7 split at the middle, as indicated at 8, to provide separate angle iron frame sections 9 and 10, arranged to be detachably connected as indicated generally by 11. The connection, as will hereinafter appear, is such as to permit the setting up and knocking down of the bed spring frame with ease and facility so that it becomes possible for a person to move the bed spring single handed and without any appreciable difficulty in getting around corners in hallways and up and down stairs. As will be noted in Fig. 1, the detachable connection is hardly at all noticeable when the bed spring is set up, due to the fact that it is contained within the angle of the angle iron frame sections.

Referring more particularly to Fig. 2, it

will be noted that the detachable connection 11 comprises a pair of blocks 12 and 13 of rectangular cross section to fit within the angle of the angle iron frame sections 9 and 10, as shown. The blocks are cast with relieved ends 14 to provide attaching portions 15 of angular cross section permitting the riveting of the blocks securely to the frame sections, as indicated at 16. Any form of attachment may be employed for assembling the blocks permanently on the frame sections. The blocks are also cast to provide heads 17 and 18 arranged to be disposed in abutting relation at the adjoining ends of the frame sections. The head 17 has a rectangular socket 19 cast therein, the walls of which taper inwardly, as shown. The head 18 has a rectangular boss 20 of complementary form to the socket 19 so as to fit wedgingly therein to provide for interengagement of the heads and properly align the frame sections. Openings 21 and 22 extending lengthwise through the heads 17 and 18 are arranged to register when the heads are interengaged so that a bolt 23 may be passed therethrough to join the heads together. The head 24 of the bolt 23 is of reduced diameter so as to be free to turn within the relieved portion 14 of the block 13 and has a slot 25 to receive a screw driver whereby the bolt may be turned in tightening or loosening the same. A large square nut 26 is threadedly received on the end of the bolt 23 and is held against turning when the bolt is tightened or loosened by reason of its engagement with the sides of the relieved portion 14 of the block 12.

It will appear from the foregoing that the attachment and detachment of the frame sections is a simple matter as the same involves a mere screw driver operation. The wedging of the boss 20 in the socket 19 rigidly interlocks the frame sections and there is little likelihood of the bed spring frame sagging under load. Furthermore, the interlocking engagement of the heads 17 relieves the bolt of any part of the load imposed on the frame and its primary function is that of drawing the frame sections together. In tightening and loosening the bolts it is rendered unnecessary to hold the nut 26 as the latter is prevented from turning by its engagement with the sides of the relieved portion of the block,

as described above. The construction is obviously simple and inexpensive as well as unbreakable.

I claim:

5. In a foldable bed spring, the combination with a pair of frame sections of angle cross section arranged to be detachably joined together, of a pair of blocks of rectangular cross section to fit within the angles 10 of the angle frame sections, said blocks being relieved to provide attaching portions of angular cross section to be secured within the angle of the angle frame sections, the blocks providing alongside the relieved portions a pair of abutting head portions whereby the blocks may be detachably joined together, one of said portions having 15 a rectangular inwardly tapering socket, the other head portion having a boss of complementary form for wedging engagement in said socket, openings provided in said head portions extending lengthwise with re-

spect to said blocks and arranged to register when said head portions are interengaged, and a bolt passing through said registering 25 openings and serving when drawn up to wedgingly interlock the head portions of said blocks and correspondingly secure the adjoining ends of the angle bed frame sections together, said bolt having the head 30 thereof of reduced diameter to be free to turn in the relieved portion of one of said blocks, and provided with a screw driver slot whereby the bolt may be turned in tightening or loosening the same, and a nut 35 in the relieved portion of the other block and threadedly engaged on said bolt and prevented from turning in the tightening or loosening of the bolt by reason of its engagement with the sides of the relieved portion of the block.

In witness of the foregoing I affix my signature.

FRANK SMITH.
